UNITED STATES PATENT OFFICE.

HARRY E. CHIPMAN, OF NEW HAVEN, CONNECTICUT.

MOLD FOR CASTING WHEELS.

No. 905,287.

Specification of Letters Patent.

Patented Dec. 1, 1908.

Application filed September 12, 1908. Serial No. 452,790.

To all whom it may concern:

Be it known that I, HARRY E. CHIPMAN, a citizen of the United States, residing at New Haven, in the county of New Haven and State of Connecticut, have invented a new and useful Improvement in Molds for Casting Wheels; and I do hereby declare the following, when taken in connection with the accompanying drawings and the letters of reference marked thereon, to be a full, clear, and exact description of the same, and which said drawings constitute part of this specification, and represent, in—

Figure 1 an end view of a mold for casting wheels constructed in accordance with my invention. Fig. 2 a perspective view of the back mold with one of the slides in position and one removed. Fig. 3 a transverse sectional view of the two molds. Fig. 4 a plan view of one of the molds with the strips removed. Fig. 5 a perspective view of one of the strips, detached. Fig. 6 a plan view of one of the dies. Fig. 7 a transverse sectional view of the same. Fig. 8 a perspective view of one of the slides. Fig. 9 a broken front view showing the method of hinging the molds to the base.

This invention relates to an improvement in molds for casting wheels, and while particularly adapted for casting trolley wheels, is applicable for casting similar devices.

The object of the invention is to form the molds from metal so that they can be used over and over again without being destroyed as in the case of sand molds; and the invention consists in the construction and combination of parts as will be hereinafter described and particularly recited in the claims.

In carrying out my invention as herein shown, I employ a bed 2 having trunnion bearings 3 mounted upon or formed integral with it. Also mounted on the base is a brace 4 and a stop 5 for the purpose as will hereinafter appear. The part of the mold corresponding to the bottom mold, but which, for convenience, I will refer to as the back mold 6, is provided on its lower edge with perforated arms 7 adapting it to be mounted upon a shaft 8 passing through the trunnions 3. The front mold 9 is similar in form and has corresponding perforated arms 10 by which it is also mounted upon the shaft 8 and so as to rock thereon. The back mold is adapted to rest against the brace 4 and so as to stand in an inclined po-

sition, while the front mold is adapted to be turned downward and may rest upon the stop 5. In the center of the face of the back mold 6 is a recess 11 adapted to receive a die 12 which may be secured therein by screws 13, the face of the die corresponding to the side of the wheel to be cast. In the center of the face of the front mold 9 is a corresponding recess 14 to receive a die 15 which is held in place by screws 16.

Secured to the upper and lower edges of the mold 6 are strips 17 and 18 forming guide ways for slides 19 and 20, the edges of these slides having tongues 21 to engage with the strips 17 and 18. The center of the inner edges of the slides 19 and 20 are formed with semi-circular ribs 21 which form the groove in the edge of the trolley wheel 22. Through the center of the dies 12 and 15 and through the molds 6 and 9 is a tapered opening 23 through which a core pin may pass to form the central opening through the trolley wheel. In the upper edge of the die is a pouring hole 24. As a convenient means for moving the slides 19 and 20, I form the face adjacent to the mold 6 with racks 25, and in the mold 6 in line with the rack 25 I arrange gears 26 which are mounted on shafts 27 which extend up through the top of the mold and which are provided with hand wheels 28 by which they may be turned and so that by turning the hand wheels the slides 19 and 20 will be moved into or out of position. As a convenient means for locking the molds together I provide one of them with a hook 29, and the other with a stud or pin 30 with which it may be engaged. Dies corresponding to the size of the wheel to be cast having been placed in their respective molds, and suitable slides 19 having been turned into position with relation thereto so as to form a mold for the wheel, the mold 9 is raised and hooked to the mold 6. Metal may then be poured into the mold and the wheel formed. When the casting is sufficiently cooled the molds are unlocked and the front mold turned down against the stop 5 which forms a rest for it. The hand wheels 28 are then turned to force the slides 19 and 20 outward, leaving the casting free to be removed from the mold 6. I thus provide simple metal molds for casting trolley or other wheels having grooved edges.

I claim:

1. The combination with the bed, of a

front and back mold hinged thereto, said molds provided with recesses, dies mounted in said recesses, slides mounted in one of said molds and adapted to be moved transversely thereon, substantially as described.

2. A mold for casting wheels comprising a back mold and a front mold hinged to a base, the face of said molds formed with recesses, dies mounted in said recesses, strips 10 secured to the back mold, slides engaged by said strips, racks in said slides, gears mounted in the rear mold for engagement with said racks, and means for turning said gears, substantially as described.

15 3. A mold for casting trolley wheels comprising a bed, trunnion bearings extending upward therefrom, a shaft extending through said trunnions, a back and front mold, said molds having perforated arms 20 at their lower edges through which said

shaft passes, said molds formed with recesses in their inner faces, dies mounted in said recesses, slides adapted to be moved transversely on the face of the back mold, said slides provided near their lower edges 25 with racks, pinions mounted in said mold for engagement with said racks, vertical shafts on which said pinions are mounted, said shafts projecting above the upper edge of the back mold, and hand wheels secured 30 to the upper ends of said shafts, substantially as described.

In testimony whereof, I have signed this specification in the presence of two subscribing witnesses.

HARRY E. CHIPMAN.
